UNITED STATES PATENT OFFICE

114,773

DESIGN FOR AN ELECTRIC HAWAIIAN GUITAR OR SIMILAR ARTICLE

Herbert S. Sunshine, New York, N. Y., assignor to Epiphone, Inc., New York, N. Y., a corporation of New York

Application February 2, 1939, Serial No. 82,720

Term of patent 7 years

To all whom it may concern:

Be it known that I, Herbert S. Sunshine, a citizen of the United States, and a resident of Jackson Heights, in the county of Queens, city and State of New York, have invented a new, original, and ornamental Design for an Electric Hawaiian Guitar or Similar Article, of which the following is a specification, reference being had to the accompanying drawing, forming a part thereof.

Fig. 1 is a top plan view of an electric Hawaiian guitar, showing my new design.

Fig. 2 is a side elevational view thereof.

I claim:

The ornamental design for an electric Hawaiian guitar or similar article, substantially as shown.

HERBERT S. SUNSHINE.
